UNITED STATES PATENT OFFICE.

HARRY J. CRINER, OF CLARINDA, IOWA, ASSIGNOR TO L. V. KOKES AND E. L. VOGELTANZ, OF ORD, NEBRASKA.

CLOTHES WRINGER.

Application filed July 17, 1925. Serial No. 44,299.

My invention relates to improvements in clothes wringers and more particularly to manually operated means for accomplishing a quick release of pressure between the wringer rolls in case clothing or a hand or other object is caught therein.

The objects of my invention are to provide a simple, inexpensive means by which the tension of the wringer rollers can be readily and quickly adjusted to a desired point and to combine therewith means for readily and quickly releasing the wringer roll tension in case of emergency or when otherwise desirable.

I accomplish these objects by the mechanism illustrated in the accompanying drawings, in which,—

Figure 1 is a front elevation of a portion of a wringer embodying my invention but showing the wringer frame and tension blocks in section on the line 1—1 of Figure 2; Fig. 2 is a vertical cross section on the line 2—2 of Figure 1 and Figure 3 is an enlarged detail showing the frame in section and showing my tension device in its released position.

Similar numerals refer to similar parts throughout the several views.

My wringer comprises a frame, 1, in which are mounted rolls, 2 and 2', in the usual way, upon shafts, 3 and 3'. Fixed bearing blocks, 4, support the shaft of the lower roll and movable tension blocks, 5, rest upon the shaft of the upper roll in the usual way.

A spring pressure bar, 6, is supported by the movable tension blocks, 5. The upper portion of the frame is channel-shaped having a central web, 1', and flanges, 8, formed integral therewith. A socket, 9, is formed at the middle of the upper portion of the web extending upwardly and provided with a longitudinal slot in which a tension screw, 10, is fitted so as to slide longitudinally of the frame. A ball, 13, is formed integral with the tension screw, 10, and of a size corresponding to the socket, 9, so as to seat closely therein.

A handle, 15, is secured to the tension screw, 10, preferably by a pin, 16, or other suitable means. A flange, 14, is preferably united to the handle and thus secured to the tension or adjusting screw, 10, and rides upon the upper surface of the socket, 9. It is obvious that the flange, 14, may be united directly to the adjusting screw, 10, without

departing from the scope of my invention. The lower end of the tension screw, 10, is threaded as shown at 11, and the threaded end of the tension screw, 10, fits into a head, 12, which is threaded internally to correspond to the threads, 11.

The lower face of the head, 12, is rounded while the sides of the head, 12, are squared to fit snugly and slide between the flanges, 8, of the frame. A saddle, 7, is suitably secured to the pressure bar, 6, preferably by a press-fit of closely fitting slots formed in the lower portion thereof, but any desired method of securing the saddle to the pressure bar may be used.

The middle of the upper face of the saddle, 7, is flat and the ends of the saddle are sharply beveled adjacent thereto. The flat upper portion, 7', of the saddle forms a seat for the lower end of the head, 12, and the beveled ends of the saddle allow a quick release.

The contour of the upper face of the saddle, 7, may be varied to suit the requirements of any particular case.

In the operation of my device, the handle, 15, is placed in the vertical position shown in Figure 1 and turned until the operation of the threads upon the head, 12, produce the desired tension upon the saddle, 7, and pressure bar, 6.

In case the wringer is clogged by clothing or in case a hand is caught between the rolls, the tension can be instantly released by striking the handle, 15, a sharp blow or by pushing it rapidly longitudinally of the frame, 1. This will cause the head, 12, to move to one end of the saddle, 7, and allow the pressure bar, 6, to move upwardly thus entirely releasing the tension between the rolls, 2 and 2'. To replace the wringer in operative position, if the tension is not too strong, the hand lever, 15, may be moved manually into a vertical position as shown in Figure 1, or if desired, the tension screw, 10, may be screwed down farther into the head, 12, until the head, 12, will move readily on the saddle, 7. After the head, 12, is seated on the saddle, 7, the tension can be increased by unscrewing the tension screw, 10, to the desired extent.

The head, 12, by reason of its straight sides, will be held from turning by the flanges, 8, of the frame. The flange, 14, will prevent the tension screw, 10, from

being displaced downwardly and the ball, 13, acting against the socket, 9, will prevent its being displaced upwardly.

It is obvious that various changes in size, shape and proportions of the various parts may be made and equivalent parts may be substituted for the spring pressure bar, saddle, movable tension blocks or frame without departing from the spirit of my invention.

I claim:

1. An adjusting and releasing mechanism for clothes wringers comprising a channeled frame with wringer rolls mounted therein, bearing blocks and movable tension blocks adjacent the shafts of the rolls, a spring pressure bar bearing upon the movable tension blocks, a saddle, a flat top and sharply sloping sides adjacent thereto, secured to the pressure bar intermediate the ends thereof, a slotted socket formed in the upper middle portion of the channeled frame, an adjusting screw slidingly mounted in the slot having united thereto a ball adapted to fit within the socket and forming a joint therewith, a head united to the lower end of the adjusting screw adapted to seat upon the saddle and a handle formed upon the upper end of the adjusting screw and rigidly secured thereto.

2. An adjusting and releasing mechanism for clothes wringers comprising a channeled frame with wringer rolls mounted therein, bearing blocks and movable tension blocks adjacent the shafts of the rolls, a spring pressure bar bearing upon the movable tension blocks, a saddle secured to the pressure bar intermediate the ends thereof, a slotted socket formed in the upper middle portion of the channeled frame, an adjusting screw slidingly mounted in the slot having united thereto a ball adapted to fit within the socket and forming a joint therewith, a head united to the lower end of the adjusting screw adapted to seat upon the saddle and a handle formed upon the upper end of the adjusting screw and rigidly secured thereto, said handle having a projecting lower portion united therewith adapted to ride upon the upper face of the slotted socket.

3. An adjusting and releasing mechanism for clothes wringers comprising a channeled frame with wringer rolls mounted therein, bearing blocks and movable tension blocks adjacent the shafts of the rolls, a spring pressure bar bearing upon the movable tension blocks, a saddle secured to the pressure bar intermediate the ends thereof, a slotted socket formed in the upper middle portion of the channeled frame, an adjusting screw slidingly mounted in the slot having united thereto a ball adapted to fit within the socket and forming a joint therewith, a head united to the lower end of the adjusting screw adapted to seat upon the

saddle and secured against turning by contact with the flanges of the channeled frame, and a handle formed upon the upper end of the adjusting screw and rigidly secured thereto.

4. An adjusting and releasing mechanism for clothes wringers comprising a channeled frame with wringer rolls mounted therein, bearing blocks and movable tension blocks adjacent the shafts of the rolls, a spring pressure bar bearing upon the movable tension blocks, a saddle secured to the pressure bar intermediate the ends thereof, a slotted socket formed in the upper middle portion of the channeled frame, an adjusting screw slidingly mounted in the slot having united thereto a ball adapted to fit within the socket and forming a joint therewith, a head united to the lower end of the adjusting screw adapted to seat upon the saddle and secured against turning by contact with the flanges of the channeled frame, and a handle formed upon the upper end of the adjusting screw and rigidly secured thereto, said handle having a projecting lower portion united therewith adapted to ride upon the upper face of the slotted socket.

5. An adjusting and releasing mechanism for clothes wringers comprising a channeled frame with wringer rolls mounted therein, bearing blocks and movable tension blocks adjacent the shafts of the rolls, a spring pressure bar bearing upon the movable tension blocks, a saddle secured to the pressure bar intermediate the ends thereof, a slotted socket formed in the upper middle portion of the channeled frame, an adjusting screw slidingly mounted in the slot having united thereto a ball adapted to fit within the socket and forming a joint therewith, a head united to the lower end of the adjusting screw adapted to seat upon the saddle, a handle formed upon the upper end of the adjusting screw and rigidly secured thereto and means for securing the head mounted upon the lower end of the adjusting screw from turning with the adjusting screw.

6. An adjusting and releasing mechanism for clothes wringers comprising a channeled frame with wringer rolls mounted therein, bearing blocks and movable tension blocks adjacent the shafts of the rolls, a spring pressure bar bearing upon the movable tension blocks, a saddle secured to the pressure bar intermediate the ends thereof, a slotted socket formed in the upper middle portion of the channeled frame, an adjusting screw slidingly mounted in the slot having united thereto a ball adapted to fit within the socket and forming a joint therewith, a head united to the lower end of the adjusting screw adapted to seat upon the saddle, a handle formed upon the upper end of the adjusting screw and rigidly secured thereto, said handle having a projecting

lower portion united therewith adapted to ride upon the upper face of the slotted socket, and means for securing the head mounted upon the lower end of the adjusting screw from turning with the adjusting screw.

7. In a clothes wringer, the combination with a channeled frame with wringer rolls mounted therein, of bearing blocks and movable tension blocks adjacent the shafts of the rolls, a spring pressure bar bearing upon the movable tension blocks, a saddle secured to the pressure bar intermediate the ends thereof, a slotted socket formed in the upper middle portion of the channeled frame, an adjusting screw slidingly mounted in the slot having united thereto a ball adapted to fit within the socket and forming a joint therewith, a head united to the lower end of the adjusting screw adapted to seat upon the saddle, a handle formed upon the upper end of the adjusting screw and rigidly secured thereto, and means secured upon the adjusting screw adapted to ride upon the upper face of the slotted socket.

8. An adjusting and releasing mechanism

for clothes wringers comprising a channeled frame with wringer rolls mounted therein, bearing blocks and movable tension blocks adjacent the shafts of the rolls, a spring pressure bar bearing upon the movable tension blocks, a saddle secured to the pressure bar intermediate the ends thereof, a slotted socket formed in the upper middle portion of the channeled frame, an adjusting screw 30 slidingly mounted in the slot having united thereto a ball adapted to fit within the socket and forming a joint therewith, a head united to the lower end of the adjusting screw 35 adapted to seat upon the saddle, a handle formed upon the upper end of the adjusting screw and rigidly secured thereto, a flange ring secured upon the adjusting screw and adapted to ride upon the upper 40 face of the slotted socket, and means for securing the head mounted upon the lower end of the adjusting screw from turning with the adjusting screw.

In testimony whereof he affixes his signature.

HARRY J. CRINER.
